(57) **CLAIM**

The ornamental design for an electrical quick connect conduit as shown and described.

DESCRIPTION

FIG. 1 is a perspective view of an electrical quick connect conduit showing my new design;

FIG. 2 is a side view thereof;

FIG. 3 is a side view thereof;

FIG. 4 is a back view thereof;

FIG. 5 is a front view thereof;

FIG. 6 is a top view thereof;

FIG. 7 is a bottom view thereof; and,

FIG. 8 is another perspective view of the electrical quick connect conduit shown in an environment of use.

The broken lines depict environment that forms no part of the claimed design.
